UNITED STATES PATENT OFFICE.

HENRY A. HARRISON, OF JAMESTOWN, NORTH DAKOTA.

STEEL SQUARE.

Application filed August 4, 1924. Serial No. 730,029.

This invention relates to improvements in carpenters' squares, and has for one of its objects to produce an implement of this character so arranged that it may be used for marking out beams and timbers in constructing hips, valleys, jack rafters, cuts for sheathing boards, stair risers and treads and the like.

Another objects of the invention is to provide an implement of this character including all the ordinary elements of a carpenter's square with the improved attachments applied, the attachments not interfering with the ordinary uses of the square.

With these and other objects in view, the invention consists in certain novel features of construction as hereinafter shown and described and then pointed out in the claims, and in the drawings illustrative of the preferred embodiment of the invention:

Figure 1 is a side elevation of the improved steel square, looking at the obverse face;

Figure 2 is a plan view, enlarged, of one of the gage blocks;

Figure 3 is a side elevation of the gage block attached to the blade portion of a square, the latter being in section on the line 3-3 of Fig. 1;

Figure 4 is a detail illustrating the manner of using the implement for lining out the angles of a piece of work, for instance a rafter;

Figure 5 is a diagram illustrating the manner of using the implement for lining out the angles in the rafters of a square dome;

Figure 6 is a detail illustrating the manner of using the implement in lining out a supporting joist in stair building;

Figure 7 is a plan view looking at the front face of the square.

The body of the improved implement is in the usual form of a carpenter's square, and comprises a blade portion 10 and a tongue portion 11, each provided with the usual scales in inches and fractions of inches, or other scales as may be required.

The blade 10 is 24 inches in length and 2 inches in width and is scaled to represent inches and fractions of inches. The tongue 11 is 16 inches in length and $11\frac{1}{2}$ inches in width, (the thickness of standard rafter timbers), and is scaled to represent inches and fractions of inches. The blade is the horizontal measurement for rafter framing, stair

stepping and brace framing, and the tongue is the vertical height in inches per foot run on the blade in laying out the pitch for the roof in roof framing and grace framing and the width of riser in stair building.

Formed through the tongue portion 11 is a relatively long longitudinally directed guide slot 12 and a plurality of sockets 13 spaced at any required distance apart.

Formed through the blade portion 10 is a like slot 14 and a plurality of sockets 15 spaced apart as shown.

For the purpose of illustration the longer slot 12 in the tongue extends from the six-inch scale line to the eight and one-half inch scale line, and the sockets 13 each extends between the nine, ten, eleven, twelve, thirteen, fourteen and fifteen inch scale lines and the respective half inch scale lines next thereto, as shown. The longitudinal slot 14 of the blade 10 is shown extending from the six inch scale line to the ten and one-half inch scale line, while the sockets 15 are shown extending from the twelve inch and seventeen inch scale lines and the respective half inch scale lines next thereto, as shown.

It will be understood that the location and lengths of the slots, and the location of the sockets may be varied as required, and I do not wish to be limited to any specific location of the slots and sockets, nor to the number employed.

Furnished with each of the squares constructed as described are a plurality of gage blocks, each formed with a head or body portion 16 of a predetermined width, for instance one-half inch when employed in association with a square having scales of inches and fractions of inches on its blade and tongue. Each of the gage blocks is formed with a lug 17 to closely engage in the sockets 13 and 15 and slidably engaging in the slots 12 and 14. Each of the lugs 17 is provided with a threaded aperture to receive a clamp screw 18, the latter each having a head 19 to bear upon the adjacent face of the blade or tongue, as the case may be.

Each gage block extends at the end farthest from the lug 17 to one edge of the blade or tongue, as shown.

One of the gage blocks may thus be associated with one of the sockets 13 or 15 and another adjustably associated with the slot 12 or 14 as will be obvious, and may be thus

changed from one socket to another, or adjusted within the slots 12 and 14 as required.

The slot 12 extending from the six inch scale line to the eight and one-half inch scale line on the tongue 11, provides that one side face of the block 16 may be set to any scale line at or between these terminal lines, for instance for marking the risers in stair building; and the other block adjusted in the slot 14 which extends from the six inch scale to the ten and one-half inch scale on the blade, to provide for the adjustment of the block for use in marking stair treads in stair building. It will be understood that the dimensions of the risers and treads may be varied by changing the relative positions of the gage blocks. In Fig. 6 is illustrated the manner of using the improved implement in laying out the tread and riser cuts in the supports in stair building. For instance, the gage block 16 of the tongue 11 is set at the point to correspond to the vertical height of the risers, for instance seven inches, and the gage block 16 of the blade 10 set to correspond to the width of the treads or steps, for instance ten inches. Then it is only necessary to apply the square, successively or progressively, to the edge of the stringer timber, a section of which is indicated at 20, as shown in Fig. 6 and marking with a scratch awl or pencil around the elbow or knee of the square, or the part which bears upon the joist, to correctly and expeditiously outline the angular sections which are to be cut out as indicated by the dotted lines at 21.

One of the sockets 15 is located between the twelve and twelve and one-half inch scale on the blade 10, and is for use in laying out a main or common rafter, and the other socket 15 is located between the seventeen inch and seventeen and one-half inch scale lines on the blade, and is for use in marking hip and valley rafters of various pitches.

The sockets 13 in the tongue are located between scale lines nine, ten, eleven, twelve, thirteen, fourteen and fifteen of the tongue and the respective half-inch scale lines of the same, and are provided for marking the rafters for a required pitch of a roof.

For instance, as illustrated in Fig. 4 a section of a rafter is illustrated at 22 with a diagram of the improved square for laying out a common rafter for a roof having a one-third pitch. Assuming that the width of the building is 24 feet and the height of the roof is 8 feet, the gauge block is set at the 12 inch scale on the blade 10 which represents one-half the width of the building and the other gauge block is set at the 8 inch scale of the tongue which represents the height of the roof. The square is then laid on the timber with the gauge blocks bearing against the edge of the timber, with

the knee or elbow of the square pointing away from you, then mark across the rafter with a scratch awl or pencil following the front of the tongue which gives the outside of plumb mark of the frame, then move the square, starting from the upper edge of the plumb mark, keeping it at the same pitch, successively as many times as there are feet in one-half of the width of the building, and at the finish cut out the rafter seat, and you have the main or common rafter for a roof having a one-third pitch.

In laying off or cutting the timber for the hip and also for the valley rafters the procedure is the same as that described for the main or common rafter except that the gauge-block for the blade is shifted from the 12 inch scale to the recess formed at the 17 inch scale which represents an angle substantially of 45 degrees. The gauge-block on the tongue remaining say at the 8 inch scale adjustment, and following the method described for the main rafter there is formed the rafter for the hip or the valley for a roof having a one-third pitch.

In forming a main or common rafter and also the hip and the valley rafter for a roof having say a one-half pitch, the gauge block of the tongue is placed in the socket or recess of the tongue formed at the 12 inch scale, and with the gauge block of the blade placed at the 12 inch scale on the blade for the main rafter, or at the 17 inch scale for the hip or the valley rafter, and proceeding in the manner described for the roof with a one-third pitch there is produced the main rafter and also the hip and valley rafters for a roof with a one-half pitch. To produce the rafters for roofs having other pitches the gauge-block of the tongue is adjusted to the scale representing the vertical height of the roof above the wall in the relation of one inch on the tongue scale to one foot run on the blade, and there is produced the main and the hip and valley rafters laid out for a roof having the roof pitch corresponding to the number of feet represented by one foot run on the blade for which the gauge-blocks have been adjusted.

The jacks and cripples for the roof are obtained in the same way. For instance, measure out of many feet of run on the blade as the jack rafter contains linear feet from the corner of the structure; if there be sixteen inch centers, measure out one foot run, slide the square along edge of the timber into position four inches more, which gives the length of the first pair; this added to every pair gives the length of each pair. The bevel to the hip is the thickness of the rafter timber, and the width of the tongue being the thickness of the timber hold the square on the plumb cut, mark along the inside edge of the tongue, at end of jack timber rafter, and at the same time mark the plumb cut

square across, and then square over, and this gives the bevel and the exact length of the jack.

- It is obvious from the foregoing that in 5 stair building it is only necessary to adjust one gauge-block in the elongated slot or recess of the tongue to the scale representing the height of the riser and the other gauge-block in the elongated slot or recess of the 10 blade representing the width of the tread and apply the square to the stringer with the blocks bearing against the edge of the timber and mark the timber following the edge of the tongue and blade and around its knee or 15 elbow, and then slide the square for the next marking and so on throughout the length of the stringer for the length desired without scaling each movement of the square. Also that in laying out the main and also the hip 20 and valley rafters for a roof of a given pitch, it is only necessary to adjust the gauge-block on the tongue to the scale which in inches represents the number of feet in height of the roof, and adjust the other gauge-block 25 on the blade to the scale which in inches represents the number of feet in one-half the width of the building, or in the same proportionate relation if the width of the building contains more feet than is represented by the 30 blade scaled one inch to one foot run, then apply the square to the rafter timber with the blocks bearing against the edge of the timber and the elbow away from you, then mark across the rafter along the front edge 35 of the tongue; then move the square along the rafter timber as many times as there are feet in one half of the width of the building and mark the timber along the front edge of the tongue in the final position of the square, 40 and take out your rafter seat. This gives you the main or common rafter for a roof having a pitch corresponding to the proportion which the scale of the location of the gauge-block on the tongue bears to one foot 45 run on the blade; that is, if the gauge-block be at the 8 inch scale on the tongue the roof will have one-third pitch, and if it be at the 12 inch scale it will have one-half pitch, and so on according as the gauge-block may be 50 positioned. For the hip and valley rafters the gauge-block of the blade will be positioned in the socket or recess at the 17 inch scale of the blade without any change in the location of the gauge-block of the tongue, 55 with the result that you get the lay out of the hip and also of the valley rafter for a roof having the same pitch. The results stated are gained without calculations and scaling necessary in the use of a steel square 60 of ordinary formation.

It will be obvious that the rafters for any required pitch may be quickly marked by adjusting the blocks to the appropriate sockets and slots.

- 65 In Figs. 1 and 7 geometrical Figures 28

and 29 are shown outlined on the square, as a matter of information.

In Fig. 5 the manner of lining out the rafters for a square dome is illustrated.

An outline or flat diagram for a dome is 70 first drawn to a scale, with the curved hip rafters represented conventionally at 23 and the spaced rafters at 24, and the curvatures of the dome indicated at 25. The spaced 75 rafters are shown terminating at the curved lines. Then by applying the improved implement to the curved lines and to the lines indicating the spaced rafters at their respective junctures as illustrated, the gage blocks can be set to enable the correct angles to be 80 scribed.

The various adjustments of the blocks 85 enables the operator to lay out any dimension or angle required.

It is to be understood that changes may 90 be made for various positions of adjustment of the gauge-blocks on the blade and on the tongue, and also in the means or manner of securing the blocks in their proper positions for the various manipulations described 95 without departing from the essential features of the invention as sought to be defined in the appended claims.

Having described my invention and set forth its merits what I claim is:— 100

1. A square having a blade and a tongue scaled to inches and fractions of inches, the blade representing horizontal measurements having formed therein an elongated recess extending between the 6 and 10 inch scale divisions, and the tongue representing vertical height having formed therein an elongated recess extending between the 6 and 8 inch scale divisions, the blade and tongue each formed with additional recesses in 105 alinement with the elongated recess of the member, and gauge-blocks adjustable in the recesses of the blade and tongue to the scale representing the horizontal measurement and scale representing the vertical height, 110 respectively, for the treads and risers for steps.

2. A square having a blade scaled in 115 inches and fractions of inches representing horizontal measurements and a tongue scaled in inches and fractions of inches representing vertical height measurements, the blade and the tongue each having an elongated recess between certain scale divisions and the blade with an independent recess between its elongated recess and end of the blade, spaced from and in alinement with the elongated recess, and the tongue formed with a plurality of independent recesses between its elongated recess and end 120 of the tongue and in alinement with the elongated recess, and gauge-blocks, one of said gauge blocks to fit to the recess in the blade and the other to fit either the elongated recess or a selected independent recess 125 130

of the tongue to obtain the proper marking of a common rafter or jack rafter for a roof having a given pitch.

3. A square having a blade scaled in 5 inches and fractions of inches representing horizontal measurements and a tongue scaled in inches and fractions of inches representing height measurements, the blade and the tongue each having an elongated recess between certain scale divisions and with an independent recess between its elongated recess and end of the blade and in alinement with the elongated recess for use in hip and valley rafter "lay-outs", and the tongue 10 formed with a plurality of recesses between its elongated recess and end of the tongue in alinement with one another and the elongated recess, and gauge-blocks, one of said gage blocks to fit to the recess in the blade and 15 the other to fit either the elongated recess or a selected recess of the tongue to obtain the proper marking of either a valley or hip rafter for a roof having a given pitch.

4. A square having a blade scaled in inches

and fractions of inches representing horizontal measurements and a tongue scaled in inches and fractions of inches representing height measurements, the blade and the tongue each having an elongated recess between certain scale divisions for conjoint use in laying out stair stringers with tread and riser cuts of a predetermined selection, and the blade and tongue provided each with certain other recesses in alinement with one another and the elongated recess for conjoint use in laying out main and hip and valley rafters and jack rafters in a structure having a roof of a predetermined pitch, and gauge-blocks for co-operation with the elongated recesses and selected recesses of the blade 25 and tongue for the "lay-out" desired, said gauge blocks each having a stud for sliding movement in the elongated recesses and proportioned to fit snugly in the selected smaller recesses.

In testimony whereof I affix my signature.

HENRY A. HARRISON.
